William Abrams INVENTOR.

UNITED STATES PATENT OFFICE.

WILLIAM ABRAMS, OF CHICAGO, ILLINOIS, ASSIGNOR TO THE MEYERCORD COMPANY,
OF CHICAGO, ILLINOIS.

DESIGN FOR A PLATE OR SIMILAR ARTICLE.

48,092.

Specification for Design.

Patented Nov. 9, 1915.

Application filed September 7, 1915. Serial No. 49,393. Term of patent 3½ years.

To all whom it may concern:

Be it known that I, WILLIAM ABRAMS, a citizen of the United States, residing at Chicago, in the county of Cook, State of Illinois, have invented a new, original, and ornamental Design for Plates or Similar Articles, of which the following is a specification, reference being had to the accompanying drawing, forming a part thereof.

The figure is a plan view of a plate broken away in part, showing my new design.

I claim—

The ornamental design for a plate, or similar article, as shown.

WILLIAM ABRAMS.

Witnesses:

F. P. VEITH,

J. CROMPTON.
